(57) **CLAIM**

The ornamental design for a countertop mold, as shown and
described.

DESCRIPTION

FIG. 1 is a front perspective view of a countertop mold
showing our new design;

FIG. 2 is a right-side elevational view of the countertop
mold shown in FIG. 1, the left-side elevational view being
a mirror image thereof;

FIG. 3 is a front elevational view of the countertop mold
shown in FIG. 1;

FIG. 4 is a rear elevational view of the countertop mold
shown in FIG. 1;

FIG. 5 is a top plan view of the countertop mold shown in
FIG. 1; and,

FIG. 6 is a bottom plan view of the countertop mold shown
in FIG. 1.

All portions of the countertop mold located between the
break lines, shown throughout the drawing disclosure, forms
no part of the claimed design.
